WILLIAM BARTHOLOMEW, OF CHICAGO, ILLINOIS, ASSIGNOR TO TROY LAUNDRY MACHINERY COMPANY, LTD., OF CHICAGO, ILLINOIS, A CORPORATION OF NEW YORK.

BALANCING MECHANISM FOR REVOLVING BODIES.

Application filed October 2, 1920. Serial No. 414,362.

To all whom it may concern:

Be it known that I, WILLIAM BARTHOLOMEW, a citizen of the United States, residing at Chicago, in the county of Cook and State 5 of Illinois, have invented certain new and useful Improvements in Balancing Mechanism for Revolving Bodies, of which the following is a specification.

This invention relates to balancing mechanism for revolving bodies.

The invention has for its object the provision of means for constantly opposing lateral deviation from the normal axis of revolution in the revolving body, for instance, a 10 shaft or spindle, and is based upon the operative principle of constantly resisting, by an annular field of radially acting sluggishly movable resistance, the tendency of the revolving body to assume an orbital path as distinguished from revolution about an immovable axis; the sectors of resistance on opposite sides of the shaft being preferably reciprocal in their action in the sense that when displacement of a resistance means 15 takes place on one side of the shaft, the resistance means on the other side move toward the center, and vice versa; that is to say, follows inward in readiness to begin its opposition to the outward leaning of the rotary body even before the latter recovers equilibrium, and thus adds to work to be overcome by the force of the over-balance, and reduces the deviation from true rotation. 20 This reciprocal action of the resistance units 25 is best insured by establishing connection diametrically across the field, and preferably by uniting all the sectors of the resistance field in an annulus of resistance, so that the revolving body will be drawn in on one sector as it pushes out on an opposite sector; and the resistance means is made double acting so that it moves sluggishly inward as well as outward and so increases the influence upon the revolving body. But the preferred connection between the units amounts 30 to more than this, and is in the nature of an annular yoke connected to all the resistance units so that the displacing and restoring movements are not only imparted to them 35 successively but distributed between adja-

cent units and their diametrically opposite units; lost motion connections between the yoke and each unit in the direction perpendicular to the radius thereof reducing the movement imparted to each in proportion 40 to the departure of the line of thrust from coincidence with the radius which defines the position of the unit.

Preferably the resistance field is composed of an annular series of individual resistance 45 units, and these are preferably of an uneven number so that the displacing effect of the resistance unit on one side will be distributed to at least two resistance units on the other side. The resistance units preferably employed consist of pistons or plungers having connection with the revolving body and working in radially disposed cylinders, and opposed in the two radial directions of their movement by fluid which escapes 50 through constricted ports and renders the pistons sluggishly responsive to radial pressure of the revolving body acting on the pistons; in other words, the resistance unit is in the nature of a double acting hydraulic 55 buffer, so connected that its reaction upon the revolving body is in a direction radial to the latter. The means for connecting up an annular series of such resistance units preferably consists of a spider or frame fitting closely upon the revolving body to be controlled, and having arms connected to the several resistance units, with compensation 60 for the lateral component of their movement or lost motion between the spider and the resistance unit in a direction transverse to the 65 radial direction of resistance.

The illustrative embodiment herein selected for disclosure of the principle of operation and one of its numerous useful applications is a centrifugal machine of the type used for extracting water in the process of 70 drying clothing in laundries.

In the accompanying drawings—

Figure 1 is a vertical axial section of a 75 centrifugal extractor embodying the several features of the invention.

Figure 2 is a horizontal section on the line 2^x—2^x of Figure 1.

Figure 3 is an enlarged detail view in 80

vertical radial section of one of the connections between a resistance unit and the spider.

Figure 4 is a plan view of parts shown in Figure 3.

Figure 5 is a section on the line 5*-5* of Figure 4; and

Figure 6 is a detail view of a cylinder, with its plunger in an extreme position.

10 Referring more in detail to the illustrative embodiment of the invention, 1 represents the spindle of a centrifugal extractor, mounted through thrust bearings 2 and radial bearings 3 in the race cage 4 which 15 is spherically stepped in the ball saddle 5 so that said spindle, while free to rotate, is laterally unrestrained by its support. 6 represents the bell shaped pulley secured to the spindle 1 and which, while depending in position to receive a belt upon its crowned periphery, also serves as a housing to surround the bearing.

Mounted upon the spindle 1 is the basket 7 within the curb 8. As thus far described, 25 the parts may follow known construction in centrifugal extractors.

In order to permit the basket 7 to yield to an unsymmetrically placed load within it and follow to the necessary extent the deviations from its true axis of revolution resultant from centrifugal force of the over balance, said spindle is surrounded by an annular series of resistance units 9, each of 30 which preferably consists of a plunger 10 working in a cylinder 11, which is supplied with oil or other suitable fluid from a surrounding reservoir, and which cylinders are provided at their ends with escape ports 12 through which the fluid may be slowly 35 expelled under pressure developed by the movement of the plunger. A port 12 at each end of each cylinder adapts the cylinders to resist the pistons in either direction, and as the pistons are connected on opposite sides 40 of the spindle the resistance units are double-acting. In the form of the device selected for illustration, the movement of the plungers 10 is radial to the spindle 1, and they are all connected with the spindle without 45 interfering with the rotation of the latter by a spider 13 and radial ball bearings 14, which spider has its arms constructed with slots 15, Figures 4 and 5, in which are fitted blocks 16 that receive the stud pins 17 rising 50 from the plungers 10. Blocks 16 fit snugly in the slots 15 in the direction which is radial to the spindles, but have freedom of movement therein in a direction perpendicular to the radius. Spiders 13 receive their 55 vertical support on balls 18 confined in cups 19 of the cover plate 20* of the annular reservoir 20 in which the cylinders 11 are located. The stud pins 17 play backward and forward in the slots 11* of the cylinders 11, in 60 the direction radial to the spindle 1, and the

relative lengths of the plungers and slots are such that an abnormal thrust of the plunger in either direction will uncover slot 11* as suggested in Figure 6, and quickly admit fluid sufficient to supply any vacuum that 70 may not have been supplied by the port 12 during the movement of the piston.

As shown in Figure 2, an uneven number of resistance units are preferably employed (five being shown) so that each unit on one 75 side of the shaft is opposed by a pair of units on the other side.

With the balancing device as above described, the orbital path of the spindle, due to unsymmetrical loading, will successively 80 force the resistance units radially outward on the side toward which the spindle leans, and draw the unit or units on the opposite side radially inward at the same time, so that the spindle is constantly opposed by a 85 sluggishly yielding and non-resilient resistance; and in the specific embodiment shown, as each unit moves outwardly two or more such resistance units on the opposite side of the spindle are drawn inwardly and 90 reset for the next outward movement; and since the units have sluggishness of movement inward as well as outward, the inward movements add to the load imposed against the spindle. In order that the resistance 95 may be regulated at will, means such as stop cocks 21 may be arranged to control the ports 12, and by such means or their equivalents the balancing effect may be regulated 100 to a nicety.

Inasmuch as the centrifugal force which throws the spindle off center is necessarily proportional to the rate of revolution, and diminishes to zero with the gradual slowing down and stopping of the revolution, the 105 force which displaces the resistance units gradually decreases with the stopping of the machine, moving each resistance unit less and less until at a time when the basket comes to rest, the spindle will always be 110 found to have assumed a substantially vertical position and the resistance units will occupy their intermediate positions as shown in Figure 1.

Any suitable means may be employed for 115 keeping the cylinders supplied with fluid, such for instance as the surrounding wall or flange 22 which provides a reservoir space 23 for each cylinder.

I claim:

1. A device for resisting deviations of a revolving body from its axis of revolution, comprising an annular field of sluggishly yielding resistance sectors, means through which it opposes movement of the revolving 125 body from its axis of revolution, and means through which the load received directly by one sector of the resistance is transmitted to another sector thereof.

2. A device for resisting deviations of a 130

revolving body from its axis of revolution, comprising an annular field of sluggishly yielding resistance sectors, means through which it opposes movement of the revolving body from its axis of revolution, and means through which the load received directly by one sector of the resistance is transmitted to another sector thereof; said resistances acting to oppose loads so transmitted as well as loads imposed directly thereon.

3. A device for resisting lateral play of a revolving body comprising an annular field of sluggishly yielding resistance units acting toward as well as away from the axis of revolution, means through which movement of the revolving body from its axis of revolution is opposed by said resistance units, and means through which movement imparted by the revolving body to the resistance units of the respective sectors of the field is also transmitted to the resistance units of opposite sectors.

4. A device for resisting deviation in revolving bodies comprising an annular field of sluggishly displaceable resistance units, means through which departure of the revolving body from its axis of revolution is opposed by a resistance unit toward which it moves, and means through which each resistance unit displaced by the revolving body is restored by displacement of a subsequently-encountered resistance unit; said resistance units being non-resilient but double acting and opposing deviation by their movements of restoration as well as movements of displacement.

5. A device for resisting deviations of a revolving body from its axis of revolution, comprising an annular field of sluggishly yielding non-resilient resistance, and means through which it opposes movement of the revolving body from its axis of revolution; the field of resistance being composed of radially disposed and radially acting resistance units; and a yoke being provided for coupling said resistance units in annular series so that thrust of deviation is distributed among a plurality of units.

6. A device for resisting deviations of a revolving body from its axis of revolution, comprising an annular field of sluggishly yielding non-resilient resistance, and means through which it opposes movement of the revolving body from its axis of revolution; the field of resistance being composed of radially disposed and radially acting resistance units; a yoke being provided for coupling said resistance units in annular series so that thrust of deviation is distributed among a plurality of units; and said yoke having lost-motion connection with the units in directions perpendicular to the radii which define their positions.

7. A device for resisting deviations of a revolving body from its axis of revolution,

comprising an annular field of sluggishly yielding non-resilient resistance, and means through which it opposes movement of the revolving body from its axis of revolution; the field of resistance comprising an annular series of hydraulic buffers.

8. A device for resisting deviations of a revolving body from its axis of revolution, comprising an annular field of sluggishly yielding non-resilient resistance, and means through which it opposes movement of the revolving body from its axis of revolution; the field of resistance comprising radially disposed hydraulic buffers and an annular yoke uniting them in series.

9. In a revolving machine having a spindle, means for resisting lateral play of said spindle, comprising a series of non-resilient resistance units and an annular yoke surrounding said spindle and having connections with said units through which they yieldingly resist movement of the spindle away from its axis of revolution, and connecting resistance units on opposite sides of the spindle to render them coacting in their resistance to the spindle.

10. In a revolving machine, a rotary spindle, means for resisting lateral play of said spindle comprising a series of radially disposed individual non-resilient resistance units and connections through which said units yieldingly resist movement of the spindle in directions radial to its axis of revolution; the connections for all the resistance units being united in rigid structure.

11. In a revolving machine, a rotary spindle, means for resisting lateral play of said spindle comprising a series of radially disposed individual resistance units and connections through which said units yieldingly resist movement of the spindle in directions radial to its axis of revolution; the connections for all the resistance units being united in rigid structure; and each resistance unit being movable relatively to its connection in a direction perpendicular to the radial direction of its action.

12. In combination with a revolving spindle supported vertically but having horizontal play, an annular yoke surrounding said spindle and in which the spindle is fitted to rotate, having radial arms, and an annular series of resistance units radially disposed about the normal position of the spindle, connected with the respective yoke arms fixedly in the directions radial to the spindle, but movably in directions perpendicular thereto.

13. In combination with a revolving spindle, an annular series of double acting sluggishly yielding resistance units symmetrically disposed around the spindle, having connections with the spindle through which they coact in resisting movement thereof from its normal axis of revolution, and be-

- ing of odd number so that the action of a resistance unit on one side of the spindle is opposed to a plurality of resistance units on the opposite side thereof.
14. In combination with an oscillatory revolving spindle, an uneven number of double acting fluid medium resistance units symmetrically disposed in annular series around the spindle, and an annular yoke in which the spindle is confined, having connection with all said units.
15. An annular field of resistance units for oscillatory revolving bodies, comprising a series of fluid cylinders and plungers contained therein, symmetrically distributed in radial positions about a common center, and connections through which said resistance units are adapted to resist departure of a revolving body from its normal axis of revolution.
16. A resistance field for oscillatory revolving bodies, comprising an annular series of resistance units and connections through which said units are adapted to resist departure of the revolving body from its normal axis of revolution; a resistance unit comprising a fluid containing cylinder, a plunger working in said cylinder, and means for restricting the escape of fluid displaced from the cylinder by the piston.
17. A resistance field for oscillatory revolving bodies, comprising an annular series

of resistance units and connections through which said units are adapted to resist departure of the revolving body from its normal axis of revolution; a resistance unit comprising a fluid containing cylinder, a plunger working in said cylinder, and means for restricting both the egress and ingress of the fluid as the piston moves in the cylinder.

18. A resistance field for oscillatory revolving bodies, comprising an annular series of resistance units and connections through which said units are adapted to resist departure of the revolving body from its normal axis of revolution; a resistance unit comprising a fluid containing cylinder, a plunger working in said cylinder, and means for restricting both the egress and ingress of the fluid as the piston moves in the cylinder, and having means for opening the cylinder for quick filling by extreme movement of the piston.

19. In a resistance mechanism for oscillatory revolving bodies, an annular series of resistance units comprising radially disposed cylinders having pistons working therein, and restricted fluid escape ports, and an oil reservoir with which said cylinders communicate.

Signed at Chicago, Illinois, this 28th day of September, 1920.

WILLIAM BARTHOLOMEW.
